POLISHING OR BUFFING WHEEL

Don H. Ross and Lawrence J. Nook, Kalamazoo,
Mich.

Application August 7, 1931, Serial No. 555,781

4 Claims. (Cl. 51—193)

The main objects of this invention are:

First, to provide a polishing or buffing wheel which is economical to produce and at the same time highly efficient.

5 Second, to provide a polishing or buffing wheel which may be subjected to severe use without burning and without injury to the work.

Third, to provide an improved polishing or buffing wheel which while highly efficient is not likely to scratch or score the work and is effective in receiving and retaining a substantial quantity of abradant or polishing powder.

Fourth, to provide a polishing or buffing wheel having these advantages which is very durable.

15 Objects relating to details and economies of our invention will appear from the description to follow. The invention is defined and pointed out in the claims.

A structure which is a preferred embodiment 20 of our invention is illustrated in the accompanying drawing, in which:

Fig. 1 is a side perspective view of our improved polishing or buffing unit.

Fig. 2 is a perspective view showing a plurality 25 of the plies of material from which our improved polishing or buffing wheel is built up.

Fig. 3 is an enlarged fragmentary section on line 3—3 of Fig. 1.

Fig. 4 is an enlarged fragmentary section illustrating a slight modification of our invention.

Fig. 5 is a fragmentary view partially in section illustrating one adaptation or embodiment of our improvements in which several units are employed as in a buffing wheel.

35 Our improved polishing or buffing wheel or unit 1 is made up of a plurality of sheets or disks of craped or crumpled parchmentized paper 2, preferably kraft paper, and a plurality of disks or sheets of cloth 3 preferably of muslin or the like.

40 These plies are arranged in superimposed relation and bound together in supporting contact, the one with the other and to form a relatively stiff unit by means of the stitching indicated at 4, the stitching being preferably a plurality of concentric rows of stitching or a spiral row of stitching extending from the center to a point adjacent the periphery of the unit. The stitches, as indicated in Figs. 3 and 4, are "through" stitches; that is, they extend from side to side and bind the plies firmly together so that they provide, as stated,

45 a relatively stiff solid unit with a plurality of the plies of the paper and a plurality of the plies of the cloth.

50 In Fig. 3, these are shown as arranged in alternating relation.

In Fig. 4, the two sheets of cloth are shown disposed side by side, the paper, however, being interposed therewith so as to form a substantial part of the body of the wheel.

The paper is, as stated, parchmentized and crumpled or craped and is preferably treated with glycerine during the process of manufacture so that it is relatively soft and does not become dry and brittle although the parchmentizing not only adds greatly to the strength of the paper but also to its durability. The glycerine treatment, however, is of advantage especially where very fine work is required. The pockets resulting from the crumpling or craping serve as effective retainers for the abradant or polishing material as the case may be.

In building up the units, the cloth plies are laid so that the threads thereof run in different directions; that is, they are disposed relative to each other so that they run in all directions; that is, one ply is turned relative to an adjacent ply so that the threads of the several plies run in all directions and are as uniformly positioned as is practical.

The paper plies are also laid so that the grain runs in various directions, one sheet being turned so that its grain runs in a direction different from that of the adjacent sheets.

The sewing is spaced according to the results desired; that is, the closer the stitches the stiffer and more solid the unit will be.

The parchmentized and craped or crumpled paper has the effect of presenting a roughened surface to the work and also to form pockets to receive the polishing material. While the wheel is very efficient, it also has a rapid cutting action, in the sense of rapid polishing. It does not score or scratch the work and it is found that cloth and paper of the character described wear uniformly.

55 In Fig. 5, we illustrate a plurality of the units 1 clamped upon the arbor 5 between supporting collars 6 and 7. The polishing or buffing wheel may be built up to the desired thickness and for certain work the single units may be employed.

The wheels may, if desired, be of very considerable diameter.

The stitching might be otherwise disposed but the circular stitching illustrated is very satisfactory.

60 Other modifications might be made but it is believed that this disclosure will enable those skilled in the art to embody or adapt our improvements as may be desired.

Having thus described our invention what we

claim as new and desire to secure by Letters Patent, is:

1. A polishing or buffing wheel unit comprising a plurality of plies of cloth and a plurality of plies of crumpled paper disposed in interspersed relation and bound together in supporting contact.

2. Buffing or polishing wheel comprising disks of paper and cloth in an arrangement of alternation whereby each disk of paper is contacted by a disk of cloth, the cloth disks being supported by the paper so that the ends of the threads of the cloth stand substantially erect in the periphery of the wheel, the cloth disks being angularly displaced to present the thread ends with substantially uniform density around the entire circumference adjacent the edges of the paper disks, the cloth disks performing a wick-like function in feeding abrasive to the cutting edges of the paper disks.

3. Buffing or polishing wheel comprising disks of crinkly paper and cloth in an arrangement of alternation in which each paper disk is flanked

on each side by a cloth disk, said wheel being compressed axially as by stitching whereby the crinkles in the paper are embossed on the cloth, clutching said paper and cloth disks together so that stresses ordinarily of tearing magnitude with respect to the paper are distributed by virtue of the inherently yielding quality of the cloth.

4. Buffing or polishing wheel comprising disks of paper and cloth in an arrangement of alternation in which each paper disk is flanked on each side by a cloth disk, the cloth disks being supported by the paper so that the ends of the threads of the cloth disks stand substantially erect in the periphery of the wheel, the cloth disks being angularly displaced to present the thread ends with substantially uniform density around the entire circumference of the wheel adjacent the edges of the paper disks, the cloth disks performing a wick-like function in feeding abrasive to the cutting edges of the paper disks.
